UNITED STATES PATENT OFFICE

OTTO BLITZ, OF OAKLAND, CALIFORNIA

CARTON

Application filed June 11, 1930. Serial No. 460,835.

This invention is for a folding carton especially adapted to the packaging of eggs and similar commodities, and has for its main object the provision of a carton which may be packed flat, quickly formed into a carton, and when the cover is closed in, forms a secured package which is not readily opened, due to the grip of the turn down portion of the cover between the duplex corner folds.

Another object of the invention is to provide a carton of the type described which is inexpensively produced and which is quickly formed into a carton without inconvenience or the adjustment or engagement of flaps or tongues.

The invention is adequately illustrated in the accompanying drawings in which

Fig. 1 is a plan view of the carton in unfolded position;

Fig. 2 is a perspective view of the carton in first fold position;

Fig. 3 indicates the final fold of the carton, and

Fig. 4 is a perspective view showing the carton with the cover flap partly inserted.

Similar reference characters are used to designate similar parts throughout the several views.

The carton blank consists of a T shaped section of cardboard as indicated in Fig. 1, and consisting of a body portion 5 and a cover portion 6. The body portion is creased at the intersection with the cover portion as at 7, and is also provided with parallel creases 8 and 9 for forming the front 10 and back 11 of the carton. A crease 12 is provided in the cover 6 to form a flap for insertion in the duplex front corners 25. Creases 13 and 14 are continuations of the sides of the cover 6, and parallel creases 15 and 16 are disposed intermediate the outer edges of the body portion and the creases 13 and 14. Diagonal creases 17 form the duplex corner folds and slits 18 permit infolding of the triangular tabs 19. The rectangular sections 20 and 21 formed by the creases form the two ends of the carton while the rectangular sections 22 and 23 form end reinforcements and end edge closures. Triangular indents 26 are formed in the cover tongue 24 for the pur-

pose of more securely retaining the tongue in the spaces 25. A thumb indent 27 permits more satisfactory engagement of the thumb when opening the carton, and the recess 28 also aids in convenient opening of the carton and serves as a thumb relief and indicator.

In forming the blank into a carton, the diagonal portions are first bent up on the creases 8 and 9, next the reinforcing portions 22 and 23 and bent up on the creases 15 and 16, followed by portions 11 and 10 which are bent up on lines 8 and 9, which partially forms the carton as indicated in Fig. 2.

The body portion is next bent up on the creases 13 and 14 forming the carton as indicated in Fig. 3, the cover being then folded over and the tongue 24 inserted in the spaces 25 as indicated in Fig. 4, securely locking the carton.

Having described an operative method of constructing and folding the carton it will be understood that variations in form may be resorted to which are consistent with the appended claims and that such variations will not detract from the spirit or scope of the invention or sacrifice any of its advantages.

What I claim is:

A folding carton formed from a T shaped blank and securely locked in folded position by insertion of the cover tongue in slots 80 formed at the front corners between the front panel and the diagonally folded corner material, said sides having inturned flanges to provide reinforcement at the top thereof, said flanges having depending diagonal tongues 85 interposed within said diagonally folded corners, said cover tongue having a series of triangular indents for engagement in said diagonally folded corners, a thumb indent in said cover tongue, a thumb recess in the front panel, said blank being creased at all bend lines, the head section of the T shaped blank having diagonal corners.

In testimony whereof I have affixed my signature.

OTTO BLITZ.
